UNITED STATES PATENT OFFICE.

WALDO JONATHAN LEE, OF MUNSON, ALBERTA, CANADA, ASSIGNOR OF ONE-HALF TO
AXEL R. OLSEN, OF MUNSON, ALBERTA, CANADA.

CLEANER FOR ROLLING COLTERS.

1,142,185.

Specification of Letters Patent.

Patented June 8, 1915.

Application filed July 3, 1914. Serial No. 848,920.

To all whom it may concern:

Be it known that I, WALDO J. LEE, a subject of the King of Great Britain, residing at Munson, in the Province of Alberta and in the Dominion of Canada, have invented a new and useful Improvement in Cleaners for Rolling Colters, of which the following is a specification.

This invention relates to a spring pressed cleaner for rolling colters in which the scrapers or cleaning members set at an angle to the sides of the colter, and are held in yielding engagement with the colter by means of suitable arranged springs.

15 The invention also consists in the novel features of construction and arrangement of parts hereinafter described, pointed out in the claims and shown in the accompanying drawings, in which:

20 Figure 1 is a side elevation. Fig. 2 is a plan view. Fig. 3 is a sectional front elevation, and Fig. 4 is a cross section through a clamping bar.

In these drawings 1 is the colter journaled 25 in the usual forked frame 2. Bars 3 rest transversely across the frame 2, said bars being longitudinally slotted as shown at 5, and the top bars, or both if desired to make them interchangeable, are recessed on their 30 inner faces as shown at 6 in Fig. 4 to receive bolt heads. Bolts 7 pass through these bars and also through suitable wedges 4, and connect the bars to each other.

Resting on the upper bar 3 and transverse 35 thereto are bars 8 longitudinally slotted as shown at 9, and locked to the top bar 3 by bolts 9^a, the heads of which rest in the recesses 6 so as to clear the frame 2.

The bars 8 are rounded adjacent their

free ends and upon these cylindrical portions are rotatably mounted arms 11 which carry scrapers or cleaning members 12, that engage opposite sides of the colter. These cleaning members are yieldably pressed against the colter by means of springs 13 coiled about the bars 8 and having each an end portion bearing on an arm 11.

The arms and scrapers set at an acute angle to the vertical sides of the colter, extending upwardly and inwardly from the bars 8.

The use and advantages of a device of this construction will be obvious to those skilled in the operation of rolling colters.

What I claim is:

1. The combination with a rolling colter, of bars extending in substantially horizontal planes parallel to and on opposite sides of said colter, arms pivotally mounted on the bars and adapted to swing in a vertical plane, springs bearing respectively on the bars and the arms, and cleaning members carried by the arms. 55

2. The combination with a rolling colter and its frame, of bars clamped thereto, a second set of bars adjustably arranged on the uppermost of the first mentioned bars, and extending parallel to and on opposite sides of the colter, springs carried by said second mentioned bars, arms extending inwardly and upwardly from said second mentioned bars, and loosely mounted thereon, and scrapers carried by said arms, said springs bearing on said arms. 65 70

WALDO JONATHAN LEE.
